(No Model.)

A. WEED.
FILE CUTTING MACHINE.

No. 600,817.

Patented Mar. 15, 1898.

UNITED STATES PATENT OFFICE.

ALFRED WEED, OF ANDERSON, INDIANA.

FILE-CUTTING MACHINE.

SPECIFICATION forming part of Letters Patent No. 600,817, dated March 15, 1898.

Application filed May 7, 1897. Serial No. 635,536. (No model.)

To all whom it may concern:

Be it known that I, ALFRED WEED, a citizen of the United States, residing at Anderson, in the county of Madison and State of Indiana, have invented certain new and useful Improvements in File-Cutting Machines, of which the following is a specification.

This invention relates to certain new and useful improvements in rasp or file cutting machines, having for its object to provide a machine which will produce a file with teeth of maximum regularity, uniformity, and efficiency; and the invention consists in the novel construction, combination, and arrangement of the parts hereinafter more particularly described.

In the accompanying drawings, forming a part of this specification, and in which like letters and numerals of reference indicate corresponding parts, Figure 1 is a sectional elevation of a file-cutting machine embodying the invention, parts being broken away; and Fig. 2 is a front elevation of the same, parts being in section. Fig. 3 is an elevation of a modification.

Attempts have heretofore been made to produce files by machinery which possess all of the advantages of the best hand-cut files, but in most instances with only partial success. In some instances the apparatus has been constructed to permit a certain play of the cutting-tool as it enters the file-blank; but usually this has been attained by a loss of the positive guiding of the tool-holder under the action of its spring or hammer. In the present invention I obviate this disadvantage by arranging the plunger or tool-holder to reciprocate at an incline in positive guides of the frame and in supporting the cutting-tool upon the holder at an incline more nearly vertical than that of the holder itself, but in the same general direction. By this arrangement at each downward stroke of the plunger the edge of the cutting-tool is given not only a downward, but also a positive forward movement as it enters the blank, resulting in the formation of clear-cut, well-defined, and uniform teeth equal to, if not superior to, those of the best hand-cut file.

Referring more particularly to the drawings, A designates the frame of the machine, having a bed-plate B, which is movable, as

usual, to carry the file or rasp blank C. The devices for accomplishing this movement of the bed-plate are well known in the art and need not be described herein.

Formed integral with the frame A, above and arranged to overhang the bed-plate, is a head D, formed with a central chamber 1 and with an inclined channel 2. Within the inclined channel 2 is adapted to reciprocate a plunger 3, provided with suitable means for depressing it, which means in the present instance consist of a gum-spring 4, interposed between the upper end of the plunger, and a disk 5, adjustable in a bracket of the frame by means of a screw 6. Devices are also provided for intermittently elevating the plunger against the action of its spring, and, as shown, these devices consist of an eccentric cam 7 within the chamber 1, carried upon a shaft 8, extending through the frame and supporting a band-wheel 9, and projecting from the side of the plunger 3 is a stud 10, arranged to be struck by the rotating cam to intermittently elevate the plunger.

Carried upon the plunger 3 at an angle thereto is the bevel-edged cutting-tool x. This tool is inclined in the same general direction as the plunger, but is set at a greater angle to the face of the bed-plate or file-blank C than is the plunger.

As shown, the cutting-tool is detachably connected to a tool-holder 12, which is itself detachably supported upon and at an angle to the plunger 3. It will be understood, however, that the cutting-tool may be carried directly upon the plunger, as shown in Fig. 3, thereby dispensing with the detachable holder 12.

From the above it will be apparent that the plunger and cutting-tool are secured in fixed relation to each other and that the plunger is arranged to reciprocate in fixed guides without lateral play, in consequence of which not only is it possible to cut teeth more uniformly, but they may be formed sharper and better than it is possible to form them by certain machines now in use.

Without limiting myself to the precise construction and arrangement of parts shown and described, I claim as my invention—

In a file-cutting machine, the combination with the frame, of a plunger adapted to re-

ciprocate in guides at an angle to the face of a file-blank, means for reciprocating the plunger, and a beveled-edge cutting-tool carried in a fixed position upon the plunger and arranged at an angle to the line of movement of the plunger, but at a less angle with respect to the perpendicular, substantially as described.

In testimony whereof I have signed my name to this specification in the presence of 10 two subscribing witnesses.

ALFRED WEED.
